CLAIM

The ornamental design for a blower nozzle attachment, as shown and described.

DESCRIPTION

FIG. 1 is a front view of a blower nozzle attachment showing my new design;

FIG. 2 is a rear view thereof.

FIG. 3 is a top plan view thereof.

FIG. 4 is a bottom view thereof.

FIG. 5 is a right side view thereof.

FIG. 6 is a left side view thereof.

FIG. 7 is a perspective view from left side thereof.

FIG. 8 is a perspective view from right side thereof.

FIG. 9 is a sectional view taken along lines 9-9 in FIG. 1; FIG. 10 is a sectional view taken along lines 10-10 in FIG. 5; and,

FIG. 11 is a perspective view thereof showing the blower nozzle attachment in use.

The features shown in broken lines in FIG. 11 depict environmental subject matter only and form no part of the claimed design.
